UNITED STATES PATENT OFFICE.

FRANK S. MILLER, DECEASED, LATE OF INDIANAPOLIS, INDIANA, BY DONALD S. MORRIS, ADMINISTRATOR DE BONIS NON, OF INDIANAPOLIS, INDIANA, ASSIGNOR TO WILLIAM LANGSENKAMP, JR., TRUSTEE.

AIR-LIFT-PUMP BOOSTER.

1,227,816.

Specification of Letters Patent.

Patented May 29, 1917.

Application filed May 20, 1916. Serial No. 98,852.

To all whom it may concern:

Be it known that FRANK S. MILLER, deceased, who before his death was a citizen of the United States, residing in Indianapolis, in the county of Marion and State of Indiana, invented a new and useful Air-Lift-Pump Booster, of which the following is a specification.

In the operation of air-lift-pumps, it was necessary in most systems before his invention that the flow of water caused by the air to be vertical or nearly so, as difficulty had always been experienced in case it was attempted to convey the mixed air and water horizontally. It had also been necessary, in order to obtain practical efficiency, that the air nozzle be submerged below the water level a distance bearing a large ratio to the total lift of the water.

It is the object of his present invention to provide a booster, whereby water may be conveyed horizontally through pipes from an air-lift pump, and whereby the ratio of the submergence of the air nozzle below the water level to the total height through which the water is to be lifted may be lessened without diminishing the efficiency of the pump. In accomplishing this object, he provided a chamber which may be lower than the final level to which the water is to be lifted, and placed this chamber so that the pipe extending upward from the air-lift pump in the well discharges into it, preferably vertically, the chamber providing a space within which the mixed air and water from the well are sufficiently quiet to separate, and this separation being made more complete by causing the discharge into the chamber to be against the under side of an umbrella located in such chamber above the water level therein. This chamber is a closed chamber, and the pressure of the air which is thus separated from the water is used to force the water thus separated out of this chamber and if desired along a horizontal pipe and to a higher water level. The air which separates from the water in the chamber collects therein above the water and is allowed to escape therefrom through a valved outlet communicating with the upper part of the chamber, the valve of which outlet is adjusted manually to permit the necessary air to escape so that an approximately constant water level within the chamber and

an approximately constant air pressure acting on the upper surface of this water are maintained. This manual valve has been found in practice to control the escape of air with sufficient precision without re-setting for long periods. It is this manual valve which in this particular distinguishes the structure of the present application from that of his prior Patent No. 1,157,998, granted October 26, 1915, which patent discloses and claims an automatic valve responsive to the water level in the chamber for controlling the air outlet from the chamber. The present invention was made during the development of the invention covered by his aforesaid patent. An application for the re-issue of the aforesaid patent was filed May 1, 1916, and bears Ser. No. 94833, in which re-issue application certain broad claims are presented covering generically both the structures shown in the aforesaid patent and the structure shown in the present application.

The present invention also contemplates a safety blow-off valve responsive to the air pressure in the chamber for permitting the escape of air therefrom when the air pressure exceeds a predetermined value. This is a safety device which operates in case the normal air outlet becomes insufficient for any reason, and is of particular use when the pump is started into operation and for a short time an excessive amount of air is collected in the chamber.

The accompanying drawing illustrates his invention. Figure 1 is a diagrammatic view showing a system embodying his invention; Fig. 2 is a vertical sectional view through the booster; and Fig. 3 is a section through the safety valve.

The air compressor 10 supplies compressed air through a reservoir 9 and a pipe 11 to the air nozzle 12 which is at a sufficient distance down in the well, and this air nozzle, which for the sake of the injector action he preferred to make in the form shown in his Patent No. 1,036,524, issued August 20, 1912, discharges air which mixes with the water in the well to produce an emulsion which rises in the pipe 13. This pipe 13 leads substantially straight upward into a booster 14 shell or chamber 14, which is air and water tight and is conveniently located in a pit 14' just below the surface of the ground. The

pipe 13 extends only part way up into the booster shell 14, but above the water level therein, and is conveniently surmounted by an umbrella 15, the umbrella and the upper 5 end of the pipe 13 conveniently being surrounded by a cylinder 16 open at both the upper and lower ends. The umbrella and the shell 14 direct the water discharged from the pipe 13 toward the bottom of the shell 14, 10 and allow this water to be separated from the air with which it is mixed. A second pipe 20 projects up through the bottom of the shell 14, and its upper end is surrounded by a hood or cylinder 21 spaced from the 15 pipe 20 and closed at its upper end. The cylinder 21 is open at its lower end, being supported above the floor of the shell 14 by legs 22, or in some other convenient manner. The pipe 20 communicates with the space in 20 the shell 14 by this open lower end of the cylinder 21, such end being below the water level in the shell 14. The pipe 20 may be connected, preferably through a check valve 23 which prevents back flow, with a suitable 25 storage reservoir 24, shown as a tank supported on a suitable framework above the level of the ground, the connection between the pipe 20 and the tank 24 including, if necessary, a horizontal pipe 25 which extends a 30 considerable distance and a vertical pipe 26 which leads from the pipe 25 to the reservoir 24. Horizontal pipes 25 up to nearly a mile in length have been used, and vertical pipes up to sixty or seventy feet high. A third 35 pipe 30 also extends into the shell 14, communicating with the upper part of the space within such shell, and in this pipe 30 is a manual valve 31 which can be adjusted manually to give any desired outlet opening 40 through the pipe 30, for permitting the desired escape of air from the upper part of such shell. The pipe 30 discharges directly to the atmosphere, and may be of any desired height above the shell 14.

45 The shell 14 is also provided at its upper part with a spring safety or blow-off valve 35, which opens outwardly to permit air to escape from the upper part of the shell 14 when the pressure in such shell exceeds a predetermined value. This safety valve is to take care of any abnormal pressure conditions, especially those which occur when the system is started into operation.

In operation, the compressed air discharged by the nozzle 12 mixes with the water in the well to form an emulsion which overflows the top of the pipe 13 into the shell or chamber 14. When so discharged, this emulsion separates within the booster shell 14 into its constituents air and water, the water falling to the bottom and the air rising to the top of the shell 14. The separation is made more effective and complete by reason of the upward discharge of this 60 overflowing air and water against the under

side of the umbrella 15, which deflects the water downward and against the open ended cylinder 16 and provides an excellent opportunity for the air to escape from the water. The pressure of this separated air on the 70 upper surface of the water causes the latter to flow up through the bottom of the cylinder 21 and into the pipe 20, the entrance to the pipe 20 being either at the top thereof or through slots 38 with which said pipe is 75 preferably provided within the cylinder 21. The pressure of the air on the water is sufficiently great to force this water through the pipe 20 and the check valve 23 and through the horizontal pipe 25 and vertical pipe 26 80 into the tank 24. The air which collects in the upper part of the booster shell 14 is permitted to escape through the pipe 30, but the valve 31 is adjusted manually so that the escape of air is sufficient to prevent an excess 85 of air within the booster chamber but insufficient to permit the pressure of the air within the booster chamber to be reduced below the necessary value for forcing the water out through the pipe 20 and into the tank 90 24. This adjustment of the valve 31 is obtained manually by opening the valve so that water is permitted to pass out therethrough and then gradually closing it until the flow of water out through such pipe 95 ceases. For uniform operation of the system this adjustment is entirely sufficient for long periods. The size of the opening which will produce the desired escape of air is dependent upon the back pressure due to the 100 head of water in the tank 24.

If for any reason the pressure within the shell 14 becomes too great, as because of the stoppage of the valve 31, the excessive pressure forces open the blow-off valve 35 105 and permits the air to escape from the upper part of the shell 14 until such pressure is reduced to normal. This condition of excess pressure almost always rises upon starting the system to operation, so that 110 the valve 31 is unable to permit the necessary escape of air to keep the pressure below the predetermined value, for in starting an excess of air is supplied to the booster shell 14. The operation of the blow-off valve 35 at this time prevents the excess pressure from bursting the booster shell.

By the arrangement described, the water may be forced horizontally for great distances, in a manner impossible hitherto with air-lift pumps, and the ratio of the submergence of the air nozzle 12 below the water level in the well to the total lift of the water is diminished because it is only 125 necessary that this ratio be maintained between the submergence and the lift of the water into the booster shell. Moreover, the water discharged into the pipe 25 and reservoir 24 is substantially free from air. 130

I claim as his invention:

1. In combination, a closed chamber, a pipe leading from a well into such chamber and opening into said chamber above the liquid level therein, an air nozzle in such pipe below such chamber, a pipe leading from such chamber and opening into such chamber below the liquid level therein, a downwardly opening hood located in said chamber and having its open lower end below the liquid level therein, said first named pipe discharging upwardly into said chamber and said last named pipe opening under said hood, said chamber having an air outlet opening therefrom which air outlet opening communicates with the chamber at a point higher than the liquid level therein, and a manually operated valve wholly controlling said air outlet opening to permit the escape of air from said chamber but to maintain a pressure greater than atmosphere in said chamber. 10
2. In combination, a closed chamber, a pipe leading from a well and discharging upwardly substantially vertically into such chamber, an air nozzle in such pipe below such chamber, a pipe leading from such chamber, a hood in such chamber over the end of said last named pipe, said hood having its lower end open below the liquid level in said chamber and having its upper end closed, a container which is connected to said last named pipe to receive the discharge therefrom, said chamber having an air outlet opening therefrom which air outlet opening communicates with the chamber at a point higher than the liquid level therein, and a manually operated valve wholly controlling said air outlet opening to permit the escape of air from said chamber but to maintain a pressure greater than atmosphere in said chamber. 20
3. In combination, a closed chamber, a pipe leading from a well into such chamber, an air nozzle in such pipe below such chamber, a pipe leading from such chamber over the end of said last named pipe, said hood having its lower end open below the liquid level in said chamber and having its upper end closed, said chamber having an air outlet opening therefrom which air outlet opening communicates with the chamber at a point higher than the liquid level therein, and a manually operated valve wholly controlling said air outlet opening to permit the escape of air from said chamber but to maintain a pressure greater than atmosphere in said chamber. 30
4. In combination, a closed chamber, a pipe leading from a well into such chamber, an air nozzle in such pipe below such chamber, a pipe leading from such chamber and opening into the main space within the chamber below the liquid level therein and by a passageway which carries the liquid from the chamber first upward and then downward, said chamber having an air outlet opening therefrom which air outlet opening communicates with the chamber at a point higher than the liquid level therein, and a manually operated valve wholly controlling said air outlet opening to permit the escape of air from said chamber but to maintain a pressure greater than atmosphere in said chamber. 40
5. In combination, a closed chamber, a pipe leading from a well into such chamber, an air nozzle in such pipe below such chamber, a pipe leading from such chamber and opening into such chamber below the liquid level therein, said chamber having a restricted air outlet opening therefrom which air outlet opening communicates with the chamber at a point higher than the water level therein so as to permit a restricted escape of air while maintaining the pressure of the retained air above atmospheric pressure, and a safety valve responsive to an excessive pressure within said chamber for permitting a greater escape of air from the chamber. 50
6. In combination, a closed chamber, a pipe leading from a well into such chamber, an air nozzle in such pipe below such chamber, a pipe leading from such chamber and opening into the main space within the chamber below the liquid level therein, said chamber having an air outlet opening therefrom which air outlet opening communicates with the chamber at a point higher than the liquid level therein, and a manually operated valve wholly controlling said air outlet opening to permit the escape of air from said chamber but to maintain a pressure greater than atmosphere in said chamber. 60

In witness whereof, I have hereunto set my hand at Indianapolis, Indiana, this 16 day of May, 1916.
